CLAIM

I claim the ornamental design for a gas tank cover, substantially as shown and described.

DESCRIPTION

FIG. 1 is a top isometric view of a gas tank cover in a first configuration.

FIG. 2 is a bottom isometric view of the gas tank cover of FIG. 1.

FIG. 3 is a front elevation view of the gas tank cover of FIG. 1.

FIG. 4 is a rear elevation view of the gas tank cover of FIG. 1.

FIG. 5 is a left side elevation view of the gas tank cover of FIG. 1.

FIG. 6 is a right side elevation view of the gas tank cover of FIG. 1.

FIG. 7 is a top plan view of the gas tank cover of FIG. 1.

FIG. 8 is a bottom plan view of the gas tank cover of FIG. 1; and,

FIG. 9 is a front elevation view of the gas tank cover of FIG. 1 in a second configuration.

The broken lines in the drawings illustrate portions of the

gas tank cover that form no part of the claimed design.

1 Claim, 9 Drawing Sheets
